ATTACHMENT FOR RIB KNITTING MACHINES

Lionel A. Morin, Laconia, N. H., assignor, by
mesne assignments, to Hemphill Company,
Pawtucket, R. I., a corporation of Massachusetts

Application October 23, 1931, Serial No. 570,733
Renewed December 14, 1935

9 Claims. (Cl. 66—9)

This invention relates to an attachment for rib knitting machines and has for its primary object to provide, in a manner as hereinafter set forth, an attachment of this character embodying a novel construction, combination and arrangement of parts through the medium of which an elastic or rubber thread may be embodied, for example, in the upper portions of stockings for the purpose of rendering unnecessary the use of garters or other extraneous means for holding stockings up, the invention, of course, contemplating the embodiment of the elastic or rubber thread in other articles, such as the cuffs of gloves and mittens, knee bands for knickers, sweater wristlets, hose or, in fact, any fabric that is knitted on a rib machine.

Another important object of the invention is to provide an attachment for rib knitting machines of the character set forth which will lay elastic yarn in the fabric between the dial and cylinder stitches in a manner to render the thread invisible from either side of the fabric, the incorporation of said elastic or rubber thread not changing the regular course of knitting the fabric.

Another important object of the invention is to provide an attachment of the character described which may be mounted for operation on any type and size of rib knitting machines without the necessity of materially altering the same structurally and with a minimum expenditure of labor.

Other objects of the invention are to provide an attachment for rib knitting machines which will be simple in construction, strong, durable, efficient and reliable in operation and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of the upper portion of a rib knitting machine showing an attachment in accordance with the present invention in position thereon.

Figure 2 is a view in elevation taken substantially at right angles to Figure 1.

Figure 3 is a view in top plan of the attachment in position on the machine.

Figure 4 is a view in top plan of the attachment with portions thereof removed.

Figure 5 is a view in top plan of a portion of

the attachment with the thread feeding arm in operative position.

Figure 6 is a detail view in perspective showing the manner in which the needles engage the rubber or elastic thread.

Figure 7 is a detail view in side elevation of the cam.

Figure 8 is a detail view in end elevation of the cam.

Figure 9 is a developed view of the cam.

Figure 10 is a detail view in plan of the feeding arm supporting plate.

Figure 11 is a detail view in top plan of the feeding arm.

Figure 12 is a plan view showing the manner in which the elastic or rubber thread is laid in the fabric.

Figure 13 is a view in top plan of a portion of the attachment with the feeding arm in retracted position.

Figure 14 is a detail view in side elevation showing the means for supporting and rocking the thread engaging hook.

Figure 15 is a view in vertical section taken substantially on the line 15—15 of Figure 14.

Figure 16 is a detail view in side elevation of the elastic or rubber thread cutter and retainer showing the same in closed position.

Figure 17 is a detail view in side elevation of the retainer or cutter showing the same in open position.

Figure 18 is a detail view in vertical section through the thread cutter and retainer showing the same in closed position with the severed thread clamped therein.

Figure 19 is a detail view in elevation showing a portion of the means for actuating the thread cutter and retainer.

Figure 20 is a detail view in side elevation of the feeding arm and its supporting structure.

Figure 21 is a detail view in top plan showing the means for actuating the pivoted plate which supports the feeding arm.

Figure 22 is a view in side elevation of the cam operated lever forming one of the elements for actuating the thread cutter and retainer.

Figure 23 is a detail view in edge elevation of the cam engaged lever constituting one of the elements for actuating the thread engaging hook.

Figure 24 is a detail view showing the link and lever arrangement for actuating the thread engaging hook from the cam.

Referring now to the drawings in detail, it will be seen that the reference numeral 1 designates generally a conventional rib knitting machine,

the same comprising a frame 2 in which is journaled a shaft 3 having pulleys 4 thereon. The shaft 3 is driven from any suitable source of power. The machine 1 further includes a ring gear 5 which is driven by a beveled gear 6 fixed on the shaft 3. Mounted on the ring gear 5, as usual, for rotation therewith is the cylinder cam ring 7 which includes an upstanding portion or neck 8. The reference numeral 9 designates the dial needles and 9' the cylinder needles of the knitting machine.

The ring gear 5 drives a beveled gear 10 which is mounted on the frame 2 and to which is fixed a comparatively small gear 11 which, in turn, drives the large gear 12. Fixed on one side of the gear 12 is an eccentric 13 upon which is operatively mounted a pawl 14 which is operatively engaged with the ratchet wheel 15 for driving said ratchet wheel in the same direction in which the gear 12 is rotating. A sprocket wheel 16 is fixed on one side of the ratchet wheel 15 and trained thereover is a pattern chain 17. The pattern chain has mounted thereon series of lugs 18, 19 and 20.

A guide 21 depends from the lower side of the table or top 22 of the machine 1 and mounted for vertical reciprocation therein and extending slidably through the table or top 22 and projecting thereabove are the pins 23, 24 and 25. Arms 26 are mounted for swinging movement in a vertical plane on the frame 2 of the knitting machine 1 and are operatively engageable with the lower ends of the pins 23, 24 and 25. Fingers 27 extend downwardly from the arms 26 in the path of the lugs 18, 19 and 20 for engagement thereby. In this manner the pins 23, 24 and 25 are operatively connected with the series of lugs 18, 19 and 20, respectively in a manner to be raised thereby.

The pins 23 and 24 operate certain parts of the knitting machine, but the pin 25 is used for operating my attachment, as will be described hereinafter.

It may be well to here state that the attachment constituting the present invention is mounted on the ring 7 and rotates therewith. A pindle 28 projects horizontally from the upstanding portion 8 of the ring 7 and journaled thereon is a cam which is designated generally by the reference numeral 29 and illustrated to advantage in Figures 7, 8 and 9 of the drawings. The cam 29 comprises a substantially cylindrical portion 30 having the circumferentially spaced lugs 31, 32, 33, 34, 35 and 36 projecting from the periphery of a flange 37 on one end of said cylindrical portion 30. Integral with the inner side of the flange 37 is a collar 38 the free side wall of which provides a cam surface 39 having the depression 40 therein. Spaced from the collar 38 and extending circumferentially of the cylindrical portion 30 and integral therewith is a segmental collar 41, the ends of which are spaced from each other. The cam 29 further includes a lug 42 on the cylindrical portion 30 extending from the segmental collar 41 to the free or outer end of said cylindrical portion 30. The innermost pin 25 is disposed in the path of the lugs 31 to 36, inclusive, of the cam 29 for rotating said cam in a step by step manner as the ring 7 of the knitting machine rotates. It will, of course, be understood that the cam is only operated when the pin 25 is in raised position, and this pin is raised in accordance with the number and arrangement of the lugs 20 on the chain 17.

A bracket 43 is fixed on the ring 7 and rigidly

secured to the free end portion of said bracket is an angular, inclined plate 44. An arm 45 is mounted for swinging movement in an inclined plane on the inclined, angular plate 44, said arm being connected thereto, as at 46. A standard 47 is mounted on the free end portion of the arm 45 and is provided with a transverse passage through which slidably extends the thread engaging hook 48. The hook 48 also is mounted for rocking movement in the standard 47. Collars 49 and 50 are fixed on the hook 48 on opposite sides of the standard 47 and a coil spring 51 encircles the hook 48 and has one end engaged with the standard 47 and its other end engaged with the collar 50 for yieldingly urging the hook 48 in a direction to engage the collar 49 with the standard 47 in a manner to frictionally retain said hook 48 against rotary movement in the standard 47.

20 A bracket 52 is mounted on the ring 7 and pivotally mounted for swinging movement on said bracket is a lever 53 (see Figure 24), said lever 53 being connected to the bracket 52 at an intermediate point. A pin 54 is mounted on the lower end portion of the lever 53 and is disposed in the path of the lug 42 of the cam 29 for engaging the lever 53 with said cam for actuation thereby. An angular arm 55 (see Figure 14) is mounted on the bracket 43 and mounted for swinging movement on said arm is a lever 56. A link 57 connects the upper end of the lever 53 to the corresponding end of the lever 56, a pin and slot connection 58 being provided between said link and the lever 56. A pitman 59 has one end pivotally connected to an intermediate portion of the arm 45 and its other end pivotally connected to an intermediate portion of the lever 56. In this manner the arm 45 is connected to the cam 29 for actuation thereby.

40 A pin 60 depends from the collar 50 on the hook 48. An angular arm 61 is mounted on the ring 7 and terminates in an inclined free end portion having therein a slot 62 in which the pin 60 is operable. The pin 60 is engageable with the ends of the slot 62 as the arm 45 approaches the limits of its movements for rocking the hook 48. This is illustrated to advantage in Figure 15 of the drawings. The arm 45 is actuated in one direction only by the cam 29. 50 A coil spring 63 actuates the arm 45 in the opposite direction.

A plate 64 is pivotally mounted, as at 65, for swinging movement in a horizontal plane on the ring 7 and mounted for swinging movement on the plate 64 is an angular thread feeding arm 66 which is pivotally connected to the plate adjacent its angle, as at 67. Formed on one end portion of the feeding arm 66 is an eye 68 through which the rubber or elastic thread 69 is slid able. The thread 69 may be unwound from a suitable spool or the like located above the knitting machine. An arm 70 is fixed on the feeding arm 66 and journaled thereon is a grooved pulley 71 under which the thread 69 passes before entering the eye 68. A coil spring 72 is operatively connected to the feeding arm 66 for yieldingly urging the same in one direction, one end of the coil spring being anchored to the plate 64 and the other end of said coil spring being anchored to the feeding arm.

An arcuate arm 73 is rigidly connected to the pivoted end portion of the plate 64. A lever 74 is pivotally connected, at an intermediate point to the free end portion of a bracket 75 on the ring 7 and a link 76 operatively connects the

lever 74, at one end, with the free end of the arcuate arm 73. A pin 77 projects from the other end portion of the lever 74 and rides on the surface 39 of the cam 29. A coil spring 78 is operatively connected with the link 76 for yieldingly urging the plate 64 in one direction and for maintaining the pin 77 in engagement with the surface 39 of the cam 29. Obviously, when the pin 77 enters the depression 40 in the surface 39 of the cam, the spring 78 is permitted to swing the plate 64 inwardly.

The reference numeral 79 designates an angular bracket on the free end portion of which is adjustably mounted a stop pin 80 the free end of which is engageable by the feeding arm 66 in a manner to limit the swinging movement of said feeding arm under impulsion by the coil spring 72. The reference numeral 81 designates generally a thread cutting and retaining unit which will be presently described in detail. When the plate 64 swings inwardly, as directed in broken lines in Figure 13 of the drawings, it carries with it the feeding arm 66 and this movement, of course, moves the feeding arm in a direction away from the stop pin 80. This permits the coil spring 72 to swing the feeding arm 66 from the position indicated in full lines in Figure 13 of the drawings to the position indicated in broken lines. Thus, the eye 68 is swung toward the unit 81.

The unit 81 comprises a suitable supporting standard 82 upon which is mounted a stationary blade 83. The unit 81 further includes a swinging blade 84 of substantially U-shaped cross section (see Figure 18) which coacts with the blade 83 for severing and then clamping or retaining the elastic or rubber thread 69. A lever 85 extends from the pivoted end of the blade 84 and pivotally connected thereto is one end of a link 86. The reference numeral 87 (Fig. 22) designates a lever which is pivotally mounted at an intermediate point and which, at one end, terminates in a down turned nose portion 88 which is adapted to ride on the periphery of the collar 41 of the cam 29 and also on the cylindrical portion 30 (Fig. 2) of said cam between the ends of the collar 41. The other end of the lever 87 is bifurcated, as at 89 and the furcations straddle the reduced extension 90 on one end of a lever 91 which is pivotally mounted intermediate its ends. The link 86 is operatively connected to the other end of the lever 91. Said lever 91 is of angular form and is mounted on a bracket 92. This is best seen in Figure 1 of the drawings. It will thus be seen that the swinging blade 84 of the unit 81 is connected to the cam 29 for actuation thereby.

It will be supposed that the machine is functioning in the usual manner and it is desired to embody the elastic or rubber thread in the fabric. The ring 7, with the attachment thereon, is rotating, of course, in a counterclockwise direction. The innermost pin 25 is raised by one of the lugs 28 on the chain 17 with the result that in the next revolution of the ring 7 the lug 31 on the cam 29 will engage said pin 25 and cause the cam to rotate a fraction of a revolution. This movement of the cam 29 causes the lug 42 on the cam to engage the pin 54 on lever 53 so that the latter is rocked and exerts a pull on the link 51 which swings the lever 56 so that the pitman 59 swings the arm 45 to the position shown in dotted lines in Fig. 4. Due to the inclination of the plate 44 to which the arm 45 is pivoted, said arm moves downwardly and near the end of its movement, the hook 48 is given a partial turning movement

by the pin 68 striking the end of the slot 62 in the arm 61, see Fig. 15, and thus the bent end of the hook is caused to engage the elastic thread 69, as shown in dotted lines in Fig. 4. When the lug 42 disengages the pin 54, the spring 68 returns the arm 45 and the hook 48 to their original positions, as shown in full lines in Fig. 4 and then near the end of this return movement, the pin strikes the other end of the slot 62 so as to turn the hook to the position shown in full lines in Fig. 4. On the return movement of the arm and hook, the elastic thread 69 assumes the position shown in dotted lines of Fig. 4, between the eye 68 and the combined cutter and clamp 84. When the hook 48 is partially turned at the end of its return movement, as shown in full lines in Fig. 4, the elastic thread is released by the hook so as to be engaged by the hooks of some of the dial needles 8 which thereby cause the said elastic thread to be incorporated in the fabric. As the ring 7 rotates around the stationary needle cylinder, the elastic thread assumes the position shown in dotted lines A in Fig. 6 and after the clamp 84 has moved a certain distance past the point where the elastic thread is held in the fabric, the end of the thread will be pulled from the clamp 84. As before stated, only a few of the needles initially cause the elastic thread to be incorporated in the fabric, the said elastic thread being thereafter inlaid between the dial and cylinder wales, the feeder 66 being back of the knitting needles and is too far away to feed the elastic thread to the needles. Consequently the feeder feeds the thread in back of the knitting needles between the dial and cylinder needles. Thus, the elastic thread is inlaid in the fabric for the rest of the revolution of the ring 7.

When the cam 29 again engages the pin 25, the engagement of the lug 31 with said pin will cause the cam to rotate another fraction of a revolution, which, with the arrangement of lugs shown, will be one-sixth of a revolution.

This movement of the cam 29 permits the pin 77 on the lever 74 to enter the depression 40 in the surface 39 of the cam 29 and permits the spring 78 to actuate the plate 64 and consequently the feeding arm 66, to the position shown in Fig. 5 and simultaneously, or substantially simultaneously, the nose 88 of the lever 87 drops from the periphery of the collar 41 of the cam 29 onto the cylindrical portion 30 for permitting the cutting and retaining unit 81 to be opened by a coil spring 92 which is connected to the lever 91. Opening of the cutting and retaining unit 81 permits the end of the feeding arm 66 upon which the eye 68 is provided to pass between the blades 83 and 84 to the position illustrated to advantage in Fig. 5 of the drawings. With the parts in the position shown in Fig. 5, the elastic thread continues to be inlaid in the fabric and as many courses of the elastic thread can be inlaid as desired. The inlaying will continue until the pin 25 is again raised by a lug 20 on the chain 17, it being understood that the pin drops to its normal position, either by gravity or by being spring-pressed, after a lug 20 on the chain 17 has passed the finger 27 of the arm 26 which is located under said pin 25. As before stated, the pins and the means for operating them are of the usual construction.

Thus the elastic thread is incorporated in the fabric by being first fed into the hooks of a few of the dial needles by the movement of the hook 48 as illustrated in Fig. 4. After the elastic has been engaged in the hooks of a few of the dial

needles, the feeder 66 is moved from the position of Fig. 4 to that of Fig. 5 after release of the elastic thread by the hook 48 as illustrated in Fig. 6. The close feeding of the elastic by the feeder 66, Fig. 5, causes the said elastic thread to be inlaid between dial and cylinder needles.

When innermost pin 25 is again raised it engages the lug 33 of the cam 29 with the result that said cam is rotated another one-sixth of a turn. This movement of the cam 29 causes the pin 11 to ride from the lowermost portion of the depression 40 toward the surface 39 of the cam 29, the rotation of said cam 29 stopping when the pin 11 is at an intermediate point, that is, when said pin is between the lowermost portion of the depression 40 and the surface 39. This swings the elastic or rubber thread feeding arm 66 outwardly toward its inoperative position and out from between the blades 83 and 84 of the cutting and retaining unit 81. When the lug 34 of cam 29 engages the pin 25 the unit 81 is swung to closed position by reason of the fact that the movement of the cam will cause the nose 88 of the lever 87 to raise to the periphery of said collar. In this manner the swinging blade 84 is swung downwardly to closed position against the tension of the coil spring 92. As the feeding arm 66 is swung away from the unit 81 and toward its inoperative position, the elastic or rubber thread 69 is still feeding through the eye 68. The engagement of the lug 34 with the pin 25 takes place upon the completion of the next or fourth revolution of the next or fourth revolution of the ring 1. Closing of the unit 81 severs the elastic or rubber thread 69 and retains one end of the same, as clearly seen in Figure 18 of the drawings. This same movement of the cam 29 returns the feeder arm 66 with the elastic thread to the inoperative position shown in Figure 4 of the drawings. As said movement of the cam 40 causes the pin 11 to move entirely out of the recess 40 upon the straight edge 39 of the part 38 of the cam, this leaves the parts in their first position ready for the incorporation of the thread 69 in the material being knitted when desired but this will not take place until the lugs 20 are placed on the chain 17.

It is believed that the many advantages of an attachment in accordance with the present invention will be readily understood, and although the 50 preferred embodiment of the invention is as illustrated and described, it is to be understood that changes in the details of construction and in the combination and arrangement of parts may be resorted to which will fall within the scope of the invention as claimed.

What is claimed is:

1. In combination with a rib knitting machine having a rotary ring, a thread feeding arm pivotally mounted on the ring for feeding an elastic thread to the needles, means mounted on the ring for severing and retaining one end of the thread at the completion of the inlaying operation, means for engaging that part of the thread between the feeding arm and the severing means with some of the needles, after which the thread is pulled from the retaining means by the rotary movement of the ring, means for simultaneously moving the severing and retaining means to inoperative position and moving the feeding arm to operative position, whereby the elastic thread is inlaid in the fabric during the operation of the machine, means for moving the feeding arm through the severing and retaining means to position a part of the thread therein, means for

closing the severing and retaining means to sever the thread, a cam member having parts thereon for operating the before-mentioned means, and means for actuating the cam member from the pattern means of the knitting machine.

2. An elastic thread inlay attachment for rib knitting machines of the type including a rotary ring, comprising a thread feeding arm pivotally mounted on the ring, a severing and retaining member, including a pair of jaws, mounted on the ring, a hook member for engaging that part of the thread between the severing and retaining member and the feeding arm with some of the needles, a cam member mounted on the ring operated by the pattern mechanism of the machine, means operated by a part of said cam member for actuating the hook member to engage said hook member with the thread, spring means for moving the hook member to a position where said member will place the thread in engagement with some of the needles, means operated by another part of the cam member for separating the jaws of the severing and retaining member, means operated by another part of the cam member for moving the feeding arm to operating position for feeding the threads between the stitches, the last-mentioned means being operated by the cam member to move the feeding arm to place a part of the thread between the severing and retaining members, when the cam member is again operated by the pattern mechanism, after which the cam member operates the jaw actuating means to close the jaws to sever the thread while retaining that part 35 passing through the feeding arm.

3. An elastic thread inlaying attachment for rib knitting machines of the type including a rotary ring, and pattern mechanism, comprising a thread receiving arm pivotally mounted on the ring, a severing and retaining member carried by the ring, means for initially engaging a part of the thread, between the retaining member and the feeding arm with some of the needles, a member actuated from the pattern mechanism, carried by the ring, means for first actuating said initial means from the last-mentioned member, means actuated from the last-mentioned member for moving the severing and retaining member to inoperative position and means actuated from the last-mentioned member for simultaneously moving the feeding arm to operating position to inlay the elastic thread in the fabric, then when the member operated from the pattern mechanism is again operated by said mechanism, the feeding arm moves to inoperative position to move part of the elastic thread in the severing and retaining member after which said member is moved to operative position to sever the thread and retain that portion leading to the feeding arm.

4. A circular knitting machine having cylinder and dial needles, means for feeding an elastic thread to the needles, and a clamp for retaining an end of an elastic thread, said clamp being located outside the circle of needles, means for engaging the elastic thread and moving the same to a position to be engaged by the hooks of some of the needles, and other means for thereafter causing the elastic thread to be moved to such a feeding position that the said elastic thread is inlaid between the dial and cylinder needles.

5. A circular knitting machine having cylinder and dial needles, means for feeding an elastic thread to the needles, and means for engaging the elastic thread and moving the same to a posi-

tion to be engaged by the hooks of some of the needles, and other means for thereafter causing the elastic thread to be moved to such a feeding position that the said elastic thread is inlaid between the dial and cylinder needles.

6. A circular knitting machine having cylinder and dial needles, means for feeding an elastic thread to the needles, and a clamp for retaining an end of an elastic thread, said clamp being located outside the circle of needles, a movable member for engaging the elastic thread outside the needle circle and moving the same to a position to be engaged by the hooks of some of the needles, and other means for thereafter causing the elastic thread to be moved to such a feeding position that the said elastic thread is inlaid between the dial and cylinder needles.

7. A circular knitting machine having cylinder and dial needles, means for feeding an elastic thread to the needles, and a movable member for engaging the elastic thread outside the needle circle and moving the same to a position to be engaged by the hooks of some of the needles, and other means for thereafter causing the elastic

thread to be moved to such a feeding position that the said elastic thread is inlaid between the dial and cylinder needles.

8. A circular knitting machine having cylinder and dial needles, means for feeding an elastic thread to the needles, and means for engaging the elastic thread and moving the same to a position to be engaged by the hooks of some of the needles and thereafter releasing the elastic thread, and other means for causing the elastic thread to be moved to such a feeding position that the said elastic thread is inlaid between the dial and cylinder needles.

9. A circular knitting machine having cylinder and dial needles and means for feeding a yarn to all the needles, in combination with supplemental means for initially feeding an elastic thread into the hooks of some of the dial needles, and supplemental means for causing such a relative movement between the elastic thread and the dial needles as to cause the said elastic thread thereafter to be inlaid between dial and cylinder needles.

LIONEL A. MORIN.
